UNITED STATES PATENT OFFICE.

GEORGE H. ROWE, OF CHICAGO, ILLINOIS, ASSIGNOR TO ELECTRO-MAGNETIC TOOL COMPANY, OF CHICAGO, ILLINOIS, A CORPORATION OF ILLINOIS.

ELECTROMECHANICAL DEVICE.

1,024,027.

Specification of Letters Patent. Patented Apr. 23, 1912.

Application filed April 26, 1911. Serial No. 623,442.

To all whom it may concern:

Be it known that I, GEORGE H. ROWE, a citizen of the United States, residing at Chicago, in the county of Cook and State of Illinois, have invented certain new and useful Improvements in Electromechanical Devices, of which the following is a specification.

My invention relates to an electro-mechanical device in which a driven element is maintained in floating, elastic relation with its driving means through the agency of a magnet, preferably an electro-magnet; and one of the primary objects of the invention is to provide a construction and arrangement of said driven elements and driving means whereby a vacuum is created, during the operation of the device, which supplements and reinforces the magnetic attraction.

A further object is to establish such a relation between the driving and driven elements that during a portion of the travel of said elements, say on the forward or working stroke, a pressure of air is created back of the driven element which reinforces the action of the magnet, while during another portion of the travel of said elements, on the back stroke for instance, this pressure is changed to a vacuum or partial vacuum which assists the magnet in moving the driven element back to its normal position with respect to the driving element.

The improvements which constitute my present invention are suitable for use particularly in connection with hammers or other percussion apparatus more especially in the construction of large heavy hammers, in which case my invention makes possible a very considerable economy in the amount of current used. It is, in fact, one of the objects of my present invention to provide an electro-mechanically operated hammer that will be able to efficiently and economically perform the sort of heavy work ordinarily done by steam hammers. The improvements concerned are, however, applicable to other types of electro-mechanical devices.

The invention has for further objects such other novel and improved constructions, arrangements and devices in electro-mechani-

cal devices and in power hammers as will be hereinafter described and claimed.

The invention is illustrated, in a preferred embodiment, in the accompanying drawings, wherein—

Figure 1 is a front elevation of the apparatus with parts shown in vertical section, Fig. 2, a side elevation; Fig. 3, a vertical section, on an enlarged scale, taken on line 3—3 of Fig. 1, looking in the direction of the arrows, and Fig. 4, a sectional plan on line 4—4 of Fig. 3.

Like characters of reference indicate like parts in the several figures of the drawings.

Referring to the drawings, 10 designates a cast iron framework terminating at the upper end in a flange 11 which supports a magnet casing consisting of the cylindrical shell 12 and the pole pieces 13, 13 secured to the shell by the screws 14. Within the magnet casing is an electro-magnet 15 wound on a spool 16.

17 designates a sleeve formed with the central openings 18 which partially insulate, magnetically, the ends of the sleeve. Preferably brass rings 19 are interposed between the pole pieces 13 and the sleeve 17. Fitted in the sleeve is a plunger 20 having a depending stem 21 to which is attached, by a dowel 22, the hammer 23 preferably formed on its under side with a dove-tailed slot adapted to receive the dove-tailed rib or flange 24 of the die 25. The die 25 on the hammer works against a die 26 fitted in a dove-tailed slot in the anvil 27.

Mounted in suitable bearings 28 on opposite sides of the frame 10 is a shaft 29 to which are keyed the wheels 30. The upper end of the sleeve 17 which is in effect a cylinder for the plunger 20, is threaded to receive the cap piece 31 which closes the end of the sleeve. A portion of the cap piece 31 is in the form of a fork 32 adapted to receive the cross beam 33 bolted thereto by means of the bolt 34. Pivoted to the ends of the cross beam 33 are connecting rods 35 eccentrically connected with wheels 30. The wheels 30 may be driven in any suitable manner as, for example, by a belt or belts (not shown).

The upper end of the sleeve 17 is formed with one or more, preferably 4, air ports 36

which register with air ports 37 in the cap piece 31. The ports 37 communicate with a discharge port 38 controlled by a check valve 39 which permits the outflow of air from port 38 but prevents, or at least checks, inflow.

The operation of the hammer shown and described is as follows: It will be understood that the winding of magnet 15 is adapted to 10 be connected with some source of supply of electric current. These connections are not shown. With the magnet energized the sleeve 17 and plunger 20 will be magnetized and the latter sustained in raised position. 15 By the rotation of shaft 29 and the crank wheels 30 reciprocating movements are imparted to the sleeve 17 and these movements result in corresponding movements of the plunger 20 and the hammer 23 attached thereto. By closing up the end of the sleeve 17 while providing air ports which communicate with the interior of the sleeve at some distance from the end thereof, and controlling such air ports by a check valve which 20 allows the escape of air but prevents inflow to the space between the closed end of the sleeve and the plunger I am enabled to supplement and reinforce the force of attraction of the magnet on both the up stroke and 25 down stroke, on the up stroke by the production of a vacuum in the space between the upper end of the sleeve and the plunger, on the down stroke by the accumulation of air pressure back of the plunger after it has 30 passed the air ports. In fact with the apparatus designed as shown there will be some pressure of air developed before the plunger closes the air ports, provided the hammer is run at a sufficiently high rate of speed, due 35 to the fact that the air space within the sleeve has a much greater cross sectional area than the aggregate cross sectional areas of the air ports. This air pressure is developed because of the lag of the plunger. In 40 the same way the sleeve on the back stroke runs ahead of the plunger and, since the check valve prevents the inflow of air into the space above the plunger, a reduction of the air pressure or partial vacuum is developed above the plunger which assists the 45 magnet in lifting the plunger and its load. It will be quite possible, by proper design of the air ports and check valve, to eliminate the development of air pressure on the down 50 stroke and employ the devices and constructions shown simply for the purpose of producing a vacuum above the plunger on the up stroke. My invention contemplates employing either the vacuum alone or the vacuum 55 in combination with the air pressure.

While I have described my invention in the preferred embodiment, it will be readily understood that modifications might be devised which would come within the scope of 60 the invention. Therefore I do not limit my-

self to the particular forms, constructions and arrangements shown and described except so far as the same are made specifically limitations on certain of the claims herein.

Preferably a rheostat 40 or other equivalent device is employed for varying the amount of current supplied to the magnet 15 and thereby varying the strength of the magnet. This capacity for varying the strength of the magnet makes it possible to 70 vary the operation of the apparatus. For example, by varying the current it is possible to change the length of the stroke of the driven element, the force with which the hammer is brought against the work, and 75 the points between which the reciprocations of the driven element take place. For example, it is desirable that the machine should be capable of such regulation that a light blow or a heavy blow may be struck as 80 may be desired. It is also desirable that there should be a regulation enabling the hammer to operate upon a thick or a thin piece of work without changing the position 85 of the anvil.

It will be understood that the relative position of the driven element with respect to the sleeve depends upon several different conditions, all of which are subject to variation, namely, the weight of the driven element, 90 the strength of the magnet, the speed at which the apparatus is run, and the pressure condition in the upper end of the sleeve. This being the case, it will be understood that the particular position of the plunger with 95 respect to the sleeve which is shown in the drawings, will not be the true position for all conditions under which the apparatus may be operated.

I do not claim herein broadly means for 10 producing a compression of the air in the upper end of the sleeve on the out stroke as this invention, in a generic sense, is claimed in my co-pending application Serial No. 562,109, filed May 18, 1910; this feature of 11 the invention being herein claimed only in connection with other features specific to the present application.

I claim:

1. In a device of the character described, 11 the combination with a driving element, of a driven element, and a magnet for maintaining the latter element in floating and elastic relation with the former; one of the elements comprising a cylinder closed at one end and the other element being fitted into said cylinder so that a relative movement between the same produces a partial vacuum which supplements the action of said magnet.

2. In a device of the character described, 12 the combination with a driving element having reciprocating movement, of a driven element, and a magnet for maintaining the latter element in floating and elastic relation 13

with the former; one of the elements comprising a cylinder closed at one end and the other element being fitted into said cylinder so that a relative movement between the 5 same produces a partial vacuum which supplements the action of said magnet.

3. In a device of the character described, the combination with a reciprocating sleeve, of a plunger fitted in said sleeve, a magnet 10 which maintains said plunger in floating elastic relation with said sleeve intermediate the ends thereof, and means adapted to close one end of the sleeve so that a relative movement between the sleeve and plunger produces a partial vacuum which supplements 15 the action of said magnet.

4. In a device of the character described, the combination with a reciprocating sleeve, one end of which is closed, of a plunger fitted 20 in said sleeve, a magnet which maintains said plunger in floating elastic relation with said sleeve intermediate the ends thereof, and a check valve on the sleeve which permits outflow of air from the space between 25 the plunger and the closed end of the sleeve while checking inflow.

5. In a device of the character described, the combination with a reciprocating sleeve which is closed at one end, a plunger fitted 30 in said sleeve, a magnet which maintains said plunger in floating elastic relation with said sleeve intermediate the ends thereof, the closed end of said sleeve being formed with an air port which communicates with 35 the interior of the sleeve at a distance from the end thereof, and a check valve controlling said air port which permits outflow while checking inflow.

6. In a device of the character described, 40 the combination with a frame, of an electromagnet supported on said frame, a sleeve slidably arranged within said magnet, a plunger in said sleeve, a driving shaft provided with cranks, a cross beam on the upper 45 end of said sleeve, connecting rods between said cross beam and cranks, the upper end of said sleeve being closed, and being formed with air ports, and a check valve which permits outflow through said ports while checking inflow.

7. In a device of the character described, the combination with a frame, of an electromagnet supported on said frame, a sleeve 55 slidably arranged within said magnet, a plunger in said sleeve, a driving shaft provided with cranks, a cross beam on the upper end of said sleeve, and connecting rods between said cross beam and cranks, the upper end of said sleeve being closed and being formed with air ports which communicate with the interior of the sleeve at a distance from the end thereof.

8. In a device of the character described, 60 the combination with a frame, of an electromagnet supported on said frame, a sleeve

slidably arranged within said magnet, a plunger in said sleeve, a driving shaft provided with cranks, a cross beam on the upper end of said sleeve, connecting rods between said cross beam and cranks, the upper end of said sleeve being closed and being formed with air ports which communicate with the interior of the sleeve at a distance from the end thereof, and a check valve which permits outflow through said ports while checking inflow. 70 75

9. In a device of the character described, the combination with a driving element, of a driven element, means for maintaining the latter element in floating and elastic relation with the former, one of the elements comprising a cylinder closed at one end and the other element being fitted into said cylinder so that a relative movement between the same produces a partial vacuum 80 which supplements the elastic relation between said elements. 85

10. In a device of the character described, the combination with a reciprocating sleeve, of a plunger fitted in said sleeve, means for maintaining the plunger in floating and elastic relation with the sleeve, and means adapted to close one end of the sleeve so that a relative movement between the sleeve and the plunger produces a partial 90 vacuum which supplements the elastic relation between said elements. 95

11. In a device of the character described, the combination with a reciprocating sleeve, of a plunger fitted in said sleeve, means for 100 maintaining the plunger in floating and elastic relation with the sleeve, and a check valve on the end of the sleeve.

12. In a device of the character described, the combination with a reciprocating sleeve, 105 of a plunger fitted in said sleeve, means for maintaining the plunger in floating and elastic relation with the sleeve, and a check valve on the end of the sleeve which allows the escape of air from said sleeve while 110 checking inflow of air thereto.

13. In a device of the character described, the combination with a reciprocating sleeve, of a plunger fitted in said sleeve, means for maintaining the plunger in floating and elastic relation with the sleeve, and means adapted to close one end of the sleeve when the plunger moves away from said end, which, when the plunger moves toward said end, allows the escape of air. 115 120

14. In a device of the character described, the combination with a reciprocating sleeve, of a plunger fitted in said sleeve, means for maintaining the plunger in floating and elastic relation with the sleeve, and means adapted to close one end of the sleeve when the plunger moves away from said end, which, when the plunger moves toward said end first allows the escape of air and thereafter prevents such escape. 125 730

15. In a device of the character described, the combination with a driving element, of a driven element, a magnet for maintaining the latter element in floating and elastic relation with the former; one of the elements comprising a cylinder closed at one end and the other element being fitted into said cylinder so that a relative movement between

the same produces a partial vacuum which supplements the action of said magnet, and 10 means for varying the strength of said magnet.
